UNITED STATES PATENT OFFICE.

OTTO H. JOBSKI, OF CLEVELAND, OHIO, ASSIGNOR TO THE STANDARD PARTS COMPANY, OF CLEVELAND, OHIO, A CORPORATION OF NEW YORK.

RIM.

Application filed July 25, 1919. Serial No. 313,176.

To all whom it may concern:

Be it known that I, OTTO H. JOBSKI, a citizen of the United States, and a resident of Cleveland, county of Cuyahoga, State of Ohio, have invented certain new and useful Improvements in Rims, of which the following is a specification.

This invention relates to vehicle wheel rims and more particularly to tire-supporting rims of the so-called "quick-detachable" type which have a tire-retaining flange at one edge, and a tire-retaining side ring adjacent the other edge which is detachably secured to the rim, to facilitate the removal or replacing of a tire.

One of the objects of the invention is to provide simple and effective means for securing the detachable side ring in position upon the rim.

Other objects of the invention and the features of novelty will be apparent from the following description, taken in connection with the accompanying drawings, in which:—

Figure 1 is a fragmentary side elevation of a rim embodying my invention, certain of the parts of the rim being broken away, to more clearly disclose the structure;

Fig. 2 is a fragmentary bottom plan view of the structure shown in Fig. 1;

Fig. 3 is a fragmentary side elevation, similar to Fig. 1, but showing a modified structure embodying my invention; and

Fig. 4 is a view in perspective of one of the parts shown in Fig. 3.

In the drawings, 11 indicates a vehicle wheel rim having a tire-securing flange 12 at one edge thereof and being provided, adjacent its other edge, with a circumferential channel or groove 13 to receive a side ring 14 which is transversely split, as shown at 15, and has a base or web portion 16 thereon which extends inwardly therefrom and is adapted to be seated in the groove 13 in interlocking relation with the outer wall 17 of the groove. Adjacent its ends, the side ring 14 is provided with lugs 18 and 19, which extend through apertures 20 and 21 which are formed in the rim at the bottom of the groove 13, and are provided with transverse slots 22 and 23, respectively, in which the ends of a locking member 24 are adapted to engage, to hold the ends of the

side ring from radially outward motion. A portion of the rear edge of each of the lugs 18 and 19 is inclined forwardly and inwardly, as shown at 25, for a purpose which will be later described, and abrupt shoulders 26 are formed on said edges adjacent the base of the ring to co-operate with the rim 55 at the ends of the apertures 20 and 21, to hold the side ring from circumferential motion on the rim. A web portion 27 between the apertures 20 and 21 serves to support the ends of the side ring and will also co-operate with the forward edges of the lugs 18 and 19 to hold the side ring from circumferential motion on the rim.

A bridge member or support 28 is secured to the channeled portion of the rim, by 70 rivets 29, or in any other suitable manner, and deflected away from the rim so as to underlie the lugs 18 and 19, when they are in seated position. The locking member 24 is pivotally mounted in the bridge member 75 28, the body portion thereof having oppositely extending tongues 30 which are adapted to engage in the slots 22 and 23 when the locking member is in the position shown in Fig. 1, but will be disengaged therefrom 80 when the member has been moved substantially ninety degrees from such position. That part of the member 24 which extends through the support 28 is preferably circular in cross-section, to form a good bearing surface, and a pintle 34 is formed on the locking member 24 and is journaled in an opening 35 in the web portion 27, to furnish a more rigid mounting of the locking member. A lever arm 31 is provided to rotate 90 the member 24 to and from locking position, and has a non-circular opening therein which fits over a correspondingly shaped portion of the member 24, the inner end of which is riveted against the lever, to hold 95 the parts in assembled relation. Adjacent its ends, the lever 31 is provided with a cupped portion 32, which is adapted to engage over the head of one or the other of the rivets 29, to hold the lever 31 and the 100 locking member 24 in ring-securing position, and an opening 33 is formed in the lever 31 so that a screw driver or other instrument may be inserted therein to facilitate the movement of the lever and the locking member to and from locking position.

In a modified structure shown in Fig. 3, the locking member 24^a may be provided with a pintle 34^a, similar to the pintle 34 shown in Fig. 1, and journaled in an opening 35^a in the web portion 27, to furnish a more rigid mounting for the locking member, and tongues 30^a are formed on the locking member, similar to the tongues 30 of the member 24, and for the same purpose. In order to rotate the locking member 24^a, a head 36 of non-circular shape, preferably hexagonal, as shown, may be provided; such head having a non-circular opening therein, in which a similarly shaped extension 37 on the locking member fits, and the inner end of the extension 37 is riveted over, as shown at 38, to engage the hexagonal head to hold the parts together.

When it is desired to replace the side ring upon the rim, one end of the ring is seated upon the rim so that the lug thereon extends through its aperture 20 or 21, and the ring is then progressively seated around the circumference of the rim, the side ring being expanded sufficiently to permit the web portion 16 of the ring to be lifted over the side wall 17 of the groove 13. If the lug on that end of the ring which is last seated does not accurately register with its aperture 20 or 21, the entry of the lug in its aperture, when radially inward pressure is applied to the end of the ring, will be facilitated by the engagement of the inclined rear edge 25 of the lug with the rim at the end of the aperture. When the lugs 18 and 19 are seated in their apertures with the shoulders 26 thereon engaging with the rim, the ring will be held from circumferential motion, and the locking member 24, or 24^a, can be turned to position the ends thereof in the slots 22 and 23 to hold the ends of the ring from radially outward motion.

Having thus described my invention, what I claim is:

1. In a vehicle wheel of the class described, the combination of a tire-carrying rim having a circumferential groove at one edge thereof, a split side ring detachably mounted in said groove, a support carried by said rim, and means for securing said side ring in position on said rim comprising a latch pivotally mounted in said support and having an axial extension thereon journaled in said rim.

2. In a vehicle wheel of the class described, the combination of a tire-carrying rim having a pair of apertures therein separated by a web portion, a split side ring detachably seated on said rim and having lugs thereon extending through said apertures, a support rigidly secured to said rim on opposite sides of said apertures and underlying said lugs, and means engaging said lugs to secure said ring in seated position comprising a rotatable member journaled in said support and said web-portion.

3. In a vehicle wheel of the class described, the combination of a tire-carrying rim apertured adjacent one edge thereof, a split side ring detachably secured on said rim and having lugs projecting inwardly through the apertured portion of said rim, a support on the interior of said rim rigidly secured thereto on opposite sides of said apertured portion, circumferentially, and underlying said lugs, and means arranged between said lugs and rotatably mounted on a radially extending axis on said support and adapted to, in one position, engage both of said lugs and prevent removal thereof from said apertured portion of the rim, and in another position, to be disengaged from said lugs.

In testimony whereof I affix my signature.
OTTO H. JOBSKI.
